UNITED STATES PATENT OFFICE

FRED ALLEN HOLLOMAN, OF PHOENIX, ARIZONA

DESIGN FOR A RADIATOR CAP

Application filed July 18, 1929. Serial No. 32,104. Term of patent 7 years.

To all whom it may concern:

Be it known that I, **FRED ALLEN HOLLOMAN**, a citizen of the United States, and a resident of Phoenix, in the county of Maricopa and State of Arizona, have invented a new, original, and ornamental Design for Radiator Caps, of which the following is a specification, reference being had to the accompanying drawing, forming part thereof.

The figure is a side elevation of a radiator cap, showing my new design, the article having a third dimension so that the opposite side thereof would present substantially the same appearance as the side view shown.

I claim:

The ornamental design for a radiator cap, as shown and described.

FRED ALLEN HOLLOMAN.
